G. HAMILTON-GRAPES

CARBURATION OF AIR FOR INTERNAL COMBUSTION ENGINES

Filed Feb. 9, 1920

Inventor.
George Hamilton-Grapes.
By John W. Grapes Atty.

UNITED STATES PATENT OFFICE.

GEORGE HAMILTON-GRAPES, OF BALWYN, MELBOURNE, VICTORIA, AUSTRALIA.

CARBURATION OF AIR FOR INTERNAL-COMBUSTION ENGINES.

Application filed February 9, 1920. Serial No. 357,190.

To all whom it may concern:

Be it known that I, GEORGE HAMILTON-GRAPES, a subject of the King of Great Britain, of Boston Road, Balwyn, Melbourne, 5 in the State of Victoria, Australia, have invented certain new and useful Improvements Relating to the Carburation of Air for Internal-Combustion Engines, of which the following is a specification.

10 The present invention is directed to the efficient vaporization of a carburetted mixture to be utilized as the power agent in the cylinders of internal combustion engines. It relates to the heating of a heavier or higher 15 boiling portion of the mixture by the use of the engine exhaust gases and it is the primary object of the invention to automatically thermostatically control the heat and in such a manner that it is possible to deliver heat to the fuel to be gasified at any 20 predetermined range of temperature from that of atmospheric up to 500 degrees Fahr., or higher irrespective of the number of engine revolutions. That is to say the liquid 25 fuel such as an ordinary commercial kerosene mixture where the heavier fractions require in the earlier stages of gasification a temperature of not less than 350 degrees Fahr., may be effectively heated and maintained 30 against subsequent condensation, throughout a wide range of engine revolutions as from 400 to 3000 per minute.

In practical use the invention achieves other and further material objects of advantage as will hereafter appear.

Broadly the invention primarily resides in a thermostatically operated valvular arrangement operating to control the amount of heated gases admitted to the region of a 40 chamber or retort in which the heavier moist particles in the carburetted mixture are trapped during passage from the carburetter to the engine.

The invention further includes as a subsidiary feature the interposition between the said chamber or retort and the delivery orifice of the carburetting device of an expansion chamber which latter is so angularly arranged relative to the mouth of the retort 50 that the heavier particles enter the latter whilst the fuel vapour is free to pass onward to the engine.

The angle of incidence of the mouth of said retort relative to the stream of the fuel mixture from the carburetter is varied in 55 different constructions according to the vola-

tility of the liquid fuel in use, being greater for fuels having heavier than for those having lighter fractions.

A further feature contemplates the combination with said retort of a final expansion chamber delivering to the engine and preferably having a capacity above that of more than one of the engine cylinders.

Another feature included herein is the provision of means at or about the before mentioned merging position effecting a high velocity and turbulence in the mixture whereby the heavier particles are deflected to the retort and the whole mixture more or less disturbed or thrown into a state of turbulence but primarily are deflected and by reason of their greater inertia are deflected into the retort.

In a practical application of these features the mixture effected in any usual form of carburetting device passes through a duct or chamber of increasing area in the direction of flow which duct merges into one relatively offset or at an angle to such direction.

This latter offset or angular duct passes angularly across the mouth of a retort chamber capable of receiving the heavy moist particles in the mixture and permitting the vapour formed therein to return in said offset duct which latter proceeds to the engine preferably through an expansion chamber having a cubical capacity in excess of and preferably twice that of any one cylinder of the engine. This expansion chamber is preferably equally restricted at each end so that the velocity of the vapour entering same is equal to that of its discharge.

The means provided for setting up turbulence and deflection adjacent to the mouth of the retort consists of one or more baffle plates which may consist of a pair of segmental shaped plates located one on either side but not in line on the wall of the above mentioned expansion duct.

The retort is jacketed to receive heated vapour from the exhaust pipe and the quantity admitted is controlled by a deflecting flap valve operated at the entrance to the said jacket and in the path of flow in a pipe carrying away the engine exhaust gases.

The disposition of said valve relative to the jacket and exhaust gas flow is automatically varied according to the temperature and this is carried out by the utilization of

the expansion factor of metal the amount of gas deflected into the jacket being controlled according to the valve positions.

The appended drawings depict an example of the invention reduced to practice but the construction and arrangement therein illustrated and herein described is not to be regarded as restrictive of the scope of my invention as defined in the claims terminating this specification.

Fig. 1 is a sectional plan.

Fig. 2 a side elevation.

Fig. 3 a vertical section on line III—

Fig. 1.

Fig. 4 is a section on line IV—Fig. 3.

Fig. 5 is enlarged view of baffle plates in initial expansion chamber.

In Fig. 1 of these drawings the circles 5 indicate the cylinders of a four cylinder internal combustion engine 6 being the exhaust manifold which for the purpose of this invention is of rectangular cross section.

The pipe 7 delivers from said manifold to pipe 8 to the atmosphere. Interposed between pipes 7 and 8 and communicating with both (see particularly Fig. 3) is a heating jacket 9 about the retort chamber 10. Communication of this jacket with the pipe 6 is valveularly controlled by flapper valve 11 attached to pivot pin 12 operated by the link 13 mounted on end of rod 14. This rod has a terminal foot 15 located within the sphere of action of expansible metal shown consisting of a series of crossed plates such as 16 free at the ends and centrally coupled. The heat imparted to said plates causes same to assume a dished or concaved form operating to lift said foot 15 and rod 14 and cause closing movement of the flapper valve 11. These metal expansion plates 16 are composed of comparatively strong non-corrosive metals and have relatively widely different co-efficients of expansion.

In view of its location at the bottom of the jacket 9 out of the direct path of the heating gases from the manifold 6 to pipe 8 the expansible metal (16) is effected by the lowest temperature obtaining in the jacket 9.

When the engine is cold the plates 16 lie in flat position and consequently the flapper valve 11 is in the fully open position shown in Fig. 3 so that at the start of the engine and until the retort is sufficiently heated, practically the whole of the exhaust gases are diverted into the jacket 9. When the retort is sufficiently heated the plates 16 operate to effect closing movement of the valve to vary the volume of exhaust gases passing through chamber 9 to maintain constant the amount of heat admitted to the jacket 9.

To vary the initial angular disposition of the flapper valve 11 in the manifold 6 the rod 14 may be entered to a greater or lesser degree in the foot 15 being screw threaded thereto for that purpose.

The carburetted mixture from any form of carburetted device is delivered into the tapering or frustrated conical chamber 17 which in turn delivers into offset passage 18 which angularly crosses the mouth 19 of the retort chamber 10 (see Fig. 1). Within the region of mergence of chamber 17 with offset passage 18 segmental baffle or deflector plates 20 are inserted in staggered relationship (see Fig. 5) to cause turbulence in the flow and deflection of the mixture and to facilitate the direction of the heavy moist particles or fuel globules into the mouth of the retort 10. In the construction illustrated these plates are attached to a short tube 20^a held to the wall of the chamber 18 by bayonet slot 20^b and grub screw 20^c. The moist particles mentioned are subjected in the retort 10 to heat to a degree effecting complete vapourization. The vapour passing out of the retort into the passage 18 is drawn along tubular chamber or pipe 21 by the air stream induced by engine suction. This tubular chamber 21 delivers through a tapering outlet 22 into the engine.

The flat flapper valve 11 may be constructed of metal capable of distortion under heat as of bi-metallic sheet so that it assumes a curve or droop at the outer edge against the outer surface of which the heated gases passing along exhaust manifold 6 impinge and act in conjunction with the plates 16 to effect closing movement of the valve 11.

By the means above described the liquid fuel spray is divided into the finest possible particles, so that each is surrounded by the best effective proportion of air. By the combination of the various features constituting the invention, a supply of dry stable mixture is furnished upon which an internal combustion engine is dependent for maximum thermal and mechanical efficiency and this is in direct proportion to the dryness of a proper charge, which should be as uniform as possible for all cylinders in every cubic inch thereof. When mixtures are wet—that is when incompletely vapourized—the air and fuel cannot be uniformly distributed to the various cylinders by the present manifold system. One cylinder will get a different charge from another, as can be easily proved by pressure gauges. There are rarely two cylinders alike as to maximum pressures in a multi-cylinder engine using wet mixtures.

By the use of this invention this fault and the carbonization that arises from the vapourization of the liquid in the presence of the burning gas when it has been admitted to the cylinder in liquid state, is remedied. Again by employing the additional mechanical mixing by spraying the wet vapour over baffle plates before the heavier portions of the fuel in their undivided state are compelled by their inertia to enter the heat-re-

tort, the resultant partially heated homogeneous mixture is enabled to pass through a lengthy unjacketed expansion chamber, or induction reservoir, without undue condensation taking place. Further a straight discharge of the sprayed fuel stream from the jet of the carburetter employed on to the baffle-plates and its effective diversion so that subsequent deposition or condensation 5 of the heavier fractions beyond the retort cannot take place before they are heat treated is also obtained.

The finely divided fuel is projected in minute globules into the retort chamber, the 15 arrangement being such that practically none of the air forming the mixture enters this chamber. The heavy fuel in the retort chamber is not subjected to superheating, as there is always a quantity of liquid fuel in 20 the retort being vaporized. Following its issuance from the chamber in vapour form the fuel mixes with the carburetted mixture or main mixture stream passing to the engine.

25 Since the superheating of the vapour is prevented by the automatic thermostatic heat regulation factor the only factor causing variations in the temperature of the resulting mixture is, with any one fuel, that 30 of variations in the proportions of the mixture. Furthermore, consistent with the state in which the fuel exists in the final mixture, the temperature of that mixture is the minimum possible and practically constant varying only within five degrees F. plus or minus 35 under all conditions of operation from idling to highest speed.

From both commercial and operative 40 points of view, the prevention of superheating of the vapour is of extreme value. All that is necessary in this direction is so to proportion the surface area of the vapourizing chamber and exhaust temperature to the 45 quality of fuel, that the result sought is attained under the least favourable conditions of operation. This being done, the temperature of the mixture is inflexible and is automatically fixed over the whole range of operation by that inherent characteristic of the 50 fuel used, its heat of vapourization.

In operating an internal combustion engine with open throttle and high speeds, less heat is needed, as the cooler the mixture the higher the volumetric efficiency, but with 55 throttle nearly closed on light loads, the mixture supply is cut down and added heat must be supplied to prevent loading up or condensation due to velocity reduction in chamber 17 and beyond and this is afforded by this invention.

Further it is fundamental that a manifold of the hot-spot type should have this heated area so designed that the heat is applied to 60 that part of the charge only which requires it for vapourization, while the remaining

part which has already been vapourized or gasified completely before reaching the hot-spot should scarcely touch this heated portion. These conditions are accomplished by the angle of incidence of the mouth of 70 the heated retort to the direction of flow of the stream of fuel mixture from the carburetter primary atomizing orifice.

I claim:

1. A fuel mixture heater comprising 75 means to effect the separation of the heavier particles of a carburetted mixture, means to change the direction of flow of the mixture, a retort at the side of the direction of flow and having a single opening into said direction changing means adjacent the point of deviation thereof, means adjacent the engine exhaust manifold to heat said retort by exhaust gases, a by-pass for said gases, a thermostatically controlled valve to control said 80 gases either to the heating means or directly to the atmosphere and a deflector to direct the heavier particles into said retort.

2. A fuel mixture heater comprising means 90 to effect the expansion of a carburetted mixture, means to change the direction of said mixture after expansion, a retort at the side of the line of flow, and having a single constricted opening into the path of flow of the mixture adjacent the point of deviation 95 thereof, means to deflect separated liquid after said expansion into said retort, means adjacent the engine exhaust manifold to heat the retort, and a thermostatically controlled valve for said last named means.

3. A fuel mixture heater, comprising an expanding chamber, a delivery pipe into which the chamber discharges and arranged at an angle thereto, deflection means in said chamber adjacent said pipe, a retort opening into said pipe adjacent said chamber and arranged to receive separated liquid from said deflecting means, a heating chamber surrounding the retort, means to conduct engine exhaust gases to said heating chamber, a by-pass for said gases to the atmosphere, and a thermostatic valve controlling the flow of engine exhaust gases either to the atmosphere or to said heating chamber.

4. A fuel mixture heater for internal combustion engines, comprising a conical expanding chamber, an arcuate pipe connected to the larger end of said chamber, a tapering outlet for said pipe, a pocket or retort opening into the side of said pipe near its junction with said chamber and through which fuel mixture does not pass, said retort arranged to receive liquid particles of fuel by reason of their inertia, and means to heat said retort by exhaust gases, said 115 pocket being out of the line of flow of fuel mixture through said pipe.

Dated this twenty-second day of December, 1919.

G. HAMILTON-GRAPES.
